CLAIM

The ornamental design for a shoe, as shown and described.

DESCRIPTION

FIG. 1 is a rear perspective view of a shoe showing my new design;
FIG. 2 is a side view thereof;

FIG. 3 is an opposite side rear perspective thereof;

FIG. 4 is an opposite side view thereof; and,

FIG. 5 is a rear view thereof.

The uneven-length broken line immediately adjacent to the bottom of the shaded area defines the bounds of the claimed design and form no part thereof. The even-length broken lines within the shaded area represent stitching that forms no part of the claimed design. The uneven-length broken lines depicting the remainder of the shoe form no part of the claimed design.
